UNITED STATES PATENT OFFICE.

CURT OBST, OF NEW YORK MILLS, NEW YORK, ASSIGNOR OF ONE-HALF TO
ERNST SCHOLL, OF SAME PLACE.

DESIGN FOR A GRATE-BAR.

SPECIFICATION forming part of Design No. 24,640, dated August 27, 1895.

Application filed July 31, 1895. Serial No. 557,781. Term of patent 7 years.

To all whom it may concern:

Be it known that I, CURT OBST, an alien citizen, having made declaration of my intention to become a citizen of the United States, residing at New York Mills, in the county of Oneida and State of New York, have invented a certain new and original Design for Grate-Bars for Furnaces; and I do declare the following to be a full, clear, and exact description of the invention.

My invention relates to a new design for grate-bars for furnaces.

In the accompanying drawings, Figure 1 is a perspective view of my grate-bar. Fig. 2 is an end view of the same.

The design consists of a grate-bar of the configuration shown in the accompanying drawings.

The leading feature of the design is a plate

1, having parallel upper and lower edges 2²⁰ and 3, beveled ends 2', rectangular projections 3' at the upper corners, the alternating vertical ribs and grooves 4 and 5, respectively, and the alternating horizontal ribs and grooves 6 and 7. The lower ends of the ribs 25 4 taper downwardly and merge into the body of the plate. A grate-bar thus constructed is very ornamental and pleasing to the eye.

What I claim is—

The design for grate bars for furnaces, as 30 herein shown and described.

In testimony whereof I affix my signature in presence of two witnesses.

CURT OBST.

Witnesses:

ERNST SCHOLL,
WM. POPE.
